W. H. Lockwood
His ATTORNEY.

UNITED STATES PATENT OFFICE.

JOE D. EASTMAN, OF INDIANAPOLIS, INDIANA.

TABLE-CLOTH HOLDER.

SPECIFICATION forming part of Letters Patent No. 643,952, dated February 20, 1900.

Application filed September 28, 1899. Serial No. 731,976. (No model.)

To all whom it may concern:

Be it known that I, JOE D. EASTMAN, of Indianapolis, county of Marion, and State of Indiana, have invented a certain new and useful Table-Cloth Holder; and I do hereby declare that the following is a full, clear, and exact description thereof, reference being had to the accompanying drawings, in which like figures refer to like parts.

10 The object of this invention is to so hold a table-cloth on a table as to keep it in place and free from wrinkles on top and hold the corners in artistically-draped folds. Without such means the corners of the table-cloth hang 15 in artistically and the table-cloth is readily disarranged on the table, so as to present an untidy appearance.

My invention consists in a distender to hold the corner-folds of the table-cloth in the desired form and also in means for attaching said distender to the corner of the table.

The full nature of my invention will be understood from the accompanying drawings and the description following of one form of 25 device embodying said invention, and the scope of said invention will be understood from the claims following the description.

In the drawings, Figure 1 is a perspective of one corner of a table with the table-cloth 30 holder in place. Fig. 2 is the same with the table-cloth also shown. Fig. 3 is a plan of the part shown in Fig. 1 on a larger scale. Fig. 4 is a vertical section on the line A A of Fig. 3.

In detail, 1 is the table-top, 2 the leg supporting one corner thereof, and 3 the table-cloth.

The form of distender, as shown, consists of a piece of tin or similar metal creased to form tapering extensions 5, having between them creases or narrow recesses 6, in which the table-cloth is wedged and held. The extensions are conical, with the large end downward, in order to hold the corner of the table-cloth in artistic folds. There are in the form 45 shown three of these conical extensions 5, the main one being central at the corner of the table and there being a subordinate one on each side of such central one. The position of the table-cloth is shown in Fig. 2 and in 50 dotted lines in Fig. 3. The exact curvature in cross-section of the extensions 5 may be altered to suit one's taste, but the purpose is

for the device to hold the folds in the exact position that the taste of one dictates. The number of extensions 5 is a matter also of 55 taste, only three, however, being here shown. It is observed that vertically the distender is of considerable length, and the creases therefore pinch the table-cloth for a sufficient distance to hold it firmly. This means of holding the crease of the table-cloth by the crease in the distender gives a naturalness to the hang of the table-cloth.

The means for securing the distender to the table, as herein shown, consists of the combination therewith of the top plate 7, resting on the top of the table at the corner, and the spring 8, bearing against the under side of the table, as is shown in Fig. 4. Said spring 8 is secured at one end to the distender and at 65 the other bears against the table. This spring arrangement enables the device to be suited to tables of varying thickness. The plate 7 on top of the table is beneath the sounding-cloth. This means for holding the distender 70 on the table does not mar or injure the same in any way. The curvature of the device as it extends down over the corner of the table is preferably so made as to conform to the shape of the table in any case. The internal 75 angle where the distender and top plate join should fit snugly on the corner of the table whatever its shape. If tin or other flexible material is used, the conformation to the corner of the table can readily be accomplished 80 when it is being placed thereon. The creases are preferably formed with a contraction, as shown in Fig. 3, in order to form yielding surfaces for grasping the table-cloth and an inner enlargement that will not too sharply 85 increase the table-cloth.

I do not wish to limit my invention to the exact form I herein show of the distender or to the means for securing it to the table or to the material stated of which it is made.

What I claim as my invention, and desire to secure by Letters Patent, is—

1. A table-cloth holder including a distender for holding the corner of the table-cloth in suitable folds while on the table, and 95 means for attaching the same to the corner of the table.

2. A table-cloth holder including a distender having a plurality of tapering exten-

sions with creases between them in which the table-cloth can be fastened, and means for so attaching the same to the corner of the table that the large ends of said tapering extensions 5 will extend downward.

3. A table-cloth holder including a distender for holding the corner of a table-cloth in suitable folds while on the table, a plate connected with the upper end of the distender adapted to rest on the corner of the

table, and a spring secured to the distender adapted to bear against the under side of the table.

In witness whereof I have hereunto affixed my signature in the presence of the witnesses 15 herein named.

JOE D. EASTMAN.
